UNITED STATES PATENT OFFICE.

JOSEPH F. BOSSERMAN, OF STAUNTON, VIRGINIA; H. H. BOSSERMAN ADMINISTRATOR
OF SAID JOSEPH F. BOSSERMAN, DECEASED.

DESIGN FOR A PHONOGRAPH CASE OR CABINET.

56,218.

Specification for Design. Patented Aug. 31, 1920.

Application filed October 8, 1919. Serial No. 329,371. Term of patent 14 years.

To all whom it may concern:

Be it known that I, JOSEPH F. BOSSERMAN, a citizen of the United States, residing at Staunton, in the county of Augusta and State of Virginia, have invented a new, original, and ornamental Design for a Phonograph Case or Cabinet, of which the following is a specification, reference being had to the accompanying drawing, forming part thereof.

The figure is a perspective view of a phonograph case or cabinet embodying my design.

I claim:

The ornamental design for a phonograph case or cabinet, as shown.

JOSEPH F. BOSSERMAN.
